UNITED STATES PATENT OFFICE.

ROBERT E. CONLIN, OF CANTON, NEW YORK.

DESIGN FOR A NASAL SYRINGE.

SPECIFICATION forming part of Design No. 25,510, dated May 19, 1896.

Application filed April 14, 1896. Serial No. 587,561. Term of patent 14 years.

To all whom it may concern:

Be it known that I, ROBERT E. CONLIN, a citizen of the United States, residing at Canton, in the county of St. Lawrence and State 5 of New York, have invented a new and original Design for a Nasal Syringe, of which the following is a specification.

This invention relates to a new and original design for a nasal syringe; and it has for its 10 object to provide a design of this character that shall be both useful and ornamental.

The leading feature of the design resides in an approximately pear-shaped body having at its widened side a pair of spaced parallel 15 limb extensions provided with outer rounded extremities and merging at their inner sides into a U-shaped crotch, a spherical figure spaced from the pear-shaped body and provided with a flattened side, and an elongated 20 cylindrical figure connecting said spherical figure and the pear-shaped body at the apex of the latter, said spherical figure, cylindrical figure, and pear-shaped body producing an outline caricature of a human being.

25 In the drawing the figure is a perspective

view of a nasal syringe embodying the herein-described design.

Referring to the accompanying drawing, 1 designates an approximately pear-shaped body having at its widened side a pair of 30 spaced parallel limb extensions 2, provided with outer rounded extremities 3 and merging at their inner sides into a U-shaped crotch 4. Spaced from the body 1 and in line therewith is a spherical figure 5, provided with a 35 flattened side 6, and an elongated cylindrical figure 7 connects the figure 5 with the body 1 at the apex of the latter, it being apparent that the body 1 and the figures 5 and 7 produce an outline caricature of a human being. 40

What I claim is—

The design for a nasal syringe herein shown and described.

In testimony that I claim the foregoing as my own I have hereto affixed my signature in 45 the presence of two witnesses.

ROBERT E. CONLIN.
